US00D911626S

(12) **United States Design Patent** (10) Patent No.: **US D911,626 S**
Brutler et al. (45) Date of Patent: **** Feb. 23, 2021**

(54) **HEADSET MOUNT ARM**

(71) Applicant: **Gentex Corporation**, Simpson, PA (US)

(72) Inventors: **Zoltan S. Brutler**, Groton, MA (US); **Michael Pearson Blundell**, Windham, NH (US); **Christopher Kent Barmore**, Arlington, MA (US)

(73) Assignee: **GENTEX CORPORATION**, Simpson, PA (US)

(**) Term: **15 Years**

(21) Appl. No.: **29/706,438**

(22) Filed: **Sep. 20, 2019**

Related U.S. Application Data

(63) Continuation of application No. 29/648,265, filed on May 18, 2018, now Pat. No. Des. 866,084.

(57) **CLAIM**

The ornamental design for a headset mount arm, as shown and described.

DESCRIPTION

FIG. 1 is a top perspective view of a headset mount arm showing our new design;

FIG. 2 is a bottom perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines immediately adjacent the shaded areas represent the bounds of the claimed design, while all other broken lines are directed to unclaimed portions and are for illustrative purposes only; the broken lines form no part of the claimed design.

1 Claim, 6 Drawing Sheets
